UNITED STATES PATENT OFFICE.

HAROLD C. SUEKERT, OF NEW YORK, N. Y., ASSIGNOR TO AUTOMOTIVE SUPPLY COMPANY, INC., OF NEW YORK, N. Y., A CORPORATION OF NEW YORK.

FLOAT-CONTROL FUEL-FEEDING APPARATUS.

Application filed June 17, 1920, Serial No. 389,723. Renewed December 27, 1922.

To all whom it may concern:

Be it known that I, HAROLD C. SUEKERT, a citizen of the United States, and a resident of the city, county, and State of New York, 5 have invented certain new and useful Improvements in Float-Control Fuel-Feeding Apparatus, of which the following is a specification.

My invention relates to a fuel feeding apparatus for feeding liquid fuel, such as gasoline, from a supply tank of an automotive device, such as an automobile; for example, to the carburetor of an internal combustion engine and more particularly to a fuel feeding apparatus controlled by means of a float.

According to the present invention the fuel pumping means is actuated from a source of pulsating pressure as, for example, by connection to the cylinder of an internal combustion engine and a float is provided in the fuel reservoir for controlling the pumping means. The rise of the float with the fuel pumped in serves to operate means for holding the pumping means stationary, or substantially stationary, thus directly preventing or decreasing the pumping of fuel temporarily and automatically releasing the same as the fuel is used up and the fuel level is reduced. With my invention 30 the pump is controlled in a direct manner by means of simple and readily constructed apparatus.

In the illustrative form shown for affording a clear understanding of my invention, 35 but not for limitation of the invention, the pumping means is mounted to reciprocate and clutch means are applied thereto and operated by a float.

In the accompanying drawing illustrating 40 said embodiment of the invention Fig. 1 is a vertical sectional view of the apparatus. Fig. 2 is a detail vertical section taken on a line at right angles to Fig. 1 and Fig. 3 is a horizontal sectional detail view taken on 45 line 3-3, Fig. 1.

The reservoir 10 has a ring 11 secured thereto about its upper end as by means of solder, or the like, to which is fastened a casting 12. The casting 12 has secured 50 thereto the downwardly and upwardly extending aligned cylinders 13 and 14. The cylinder 13 is preferably located within the reservoir 10 and cylinder 14 preferably extends upwardly thereabove and has cooling fins 15. The member 12 is provided with an

upwardly extending boss 16 having formed therein a passage 17 which is connected with a source of pulsating pressure, as a cylinder of an internal combustion engine, and a downwardly extending boss 18 provided 60 with a passage 19 distinct from passage 17 and serving as a fuel inlet.

A piston 20 is provided with a flange or skirt 21 and is adapted to reciprocate upon the boss 16 within the cylinder 14, and a 65 pump cup 22 is secured to piston 20 to reciprocate therewith, by means of connecting rod 23, 23. The boss 18 is received within the flange or skirt 24 of the pump cup 22 and said boss is provided with a flexible washer 70 25 which bears directly against the skirt 24 of cup 22 and is adapted to prevent the gasoline or fuel from passing backwardly into the cup 22 from the reservoir upon the downward movement of the reciprocable 75 pumping device including piston 22, connecting rods 23, 23 and cup 24.

A check valve may be provided, if desired, in the inlet passage 19, but same is not essential, since, while with the construction 80 shown more or less fuel may pass back through the comparatively narrow passage 19 on the upward stroke of the pump a considerable portion thereof will nevertheless pass out through the opening of relatively 85 great cross section around the washer 25, as will be readily understood.

Bumpers 26 and 27 of cork, or similar material, are provided in the top part of cylinder 14 and in the bottom of cylinder 90 13 respectively and serve to cushion the reciprocable pumping means against violent shocks in each direction. The large size of the bumpers made available by the construction described is a feature of advantage because of the exceptionally long useful life 95 of the apparatus thereby obtained.

Fuel pumped into cylinder 13 is discharged into reservoir 10 through passages 28. Means are provided for venting the apparatus when in operation and also serving for keeping it closed to prevent loss by evaporation when not in operation. In the form shown, a vent hole 29 is formed in a cap 30 on cylinder 14 and the cylinder head is 100 provided within cap 30 with a valve seat 31 on which is received a valve 32 secured by means of a spring 33 to the head of piston 20.

When the device is in operation, the valve 110

32 is off its seat a considerable portion of the time and when the apparatus is not being operated the spring 33 acts to hold the valve 32 down to its seat whereby evaporation is prevented. This is a feature of considerable importance, particularly when an automobile, for example, equipped therewith is left to stand out of use for some time.

10 Springs 34, 34, which are less powerful than springs 35, 35 opposed thereto, serve as additional bumpers or shock preventing devices, while said springs 35, 35 exert pressure to hold the reciprocable pumping means downwardly against the actuating pressure 15 exerted upon the underside of piston 20 and to thereby assist in producing the reciprocating movement of the pumping mechanism.

As the piston 20 is always subject to the pulsating pressure applied thereto, means 20 are provided for temporarily rendering the device inactive by directly holding it against movement when the fuel level in the reservoir has reached a predetermined height. In the form shown, a rod 36 projects downwardly from the pump cup 22 to which it is 25 attached and extends into the interior of the reservoir 10 through an opening in the bottom of cylinder 13 where it is adapted to be engaged by a plurality of cams 37, 37 having overweighted arms 38, 38; said arms are 30 adapted to be engaged and raised by the float 39, thus clamping the rod 36 and holding it stationary, or substantially so, until 35 released by the float 39 upon the fuel level being reduced, resulting in the lowering of float 39.

The fuel outlet is preferably through a siphon, the preferred form comprises opening 40 in the tube 41 upon which the float 39 is slidably mounted, the annular passage 42 between the tube 41 and the interior of tube 43, openings 44 into the bore of tube 43 and the said bore 45. A tube 46 of relatively small diameter and open at the top extends 45 downwardly within tube 43 to below the openings 41 and serves to permit the discharge of any air or gases which might accumulate in the reservoir 10, if it should happen that same have not been discharged 50 through the vent opening 29.

It is to be understood that the invention is not limited to the form shown for the purposes of illustration but that modifications and changes may be resorted to, utilizing 55 the principle of the invention and com-

ing within the scope of the claims by which my invention is defined.

I claim:

1. In a fuel feeding apparatus, fuel pumping means adapted to be operated from a 60 source of pulsating pressure, a reservoir for fuel, and mechanical holding means controlled by the height of the fuel within the reservoir for positively holding the pumping means stationary, or substantially so. 65

2. In a fuel feeding apparatus, fuel pumping means adapted to be operated from a source of pulsating pressure, a reservoir for fuel pumped, a clutch adapted to hold said pumping means relatively stationary, or substantially so, and a float rising and falling with the rise and fall of fuel in the reservoir 70 for controlling said clutch means.

3. In a fuel feeding apparatus, fuel pumping means adapted to be connected to and 75 operated by the pulsating pressure of a cylinder of an internal combustion engine, a reservoir for fuel pumped, a clutch for holding the pumping means, and a float in the fuel reservoir for operating said clutch. 80

4. In fuel feeding apparatus, fuel pumping means comprising a piston adapted to be operated by the pulsating pressure of an internal combustion cylinder or cylinders, a reservoir for fuel pumped, a float in said 85 reservoir, a member connected to move with the piston and extending into said reservoir, and holding means to be applied to said member to hold said member and piston stationary or substantially so and adapted to 90 be actuated by said float when it rises with rise of fuel in the reservoir.

5. In a fuel feeding apparatus, a reservoir, a closure therefor having cylinders projecting into and out beyond the end of the 95 reservoir respectively, a fuel pump in the inner cylinder, piston in the outer cylinder direct connected to said fuel pump to move therewith, said piston being adapted to be actuated by the pulsating pressure of an internal combustion engine, bumpers in said 100 cylinders for cushioning the pumping mechanism against shocks, an air vent for said reservoir, a valve for the air vent, and spring means between for connecting said 105 piston to said valve.

In testimony that I claim the foregoing, I hereto set my hand, this 12 day of June, 1920.

HAROLD C. SUEKERT.
